BOBBIN RECEPTACLE SUPPORT

George F. Belforti, Milford, Mass.

Refiled for abandoned application Serial No. 537,571, May 27, 1944. This application May 24, 1945, Serial No. 595,532

8 Claims. (Cl. 139—255)

1

The present invention relates to the bobbin receptacles for looms and, as illustrated herein, relates more particularly to supports for such receptacles which permit ready removal and replacement out of and into bobbin receiving position on a loom.

This application is refiled for applicant's abandoned application, Serial No. 537,571 filed May 27, 1944.

Receptacles are provided, in automatic looms, to receive and collect empty filling carriers or bobbins as they are projected from the shuttle by an incoming filled bobbin or filling carrier. These receptacles are usually positioned below the shuttle box of the loom to receive the empty bobbins and are usually so located that they do not obstruct the passageway between the looms. It is difficult to reach into such receptacles when they are in bobbin receiving position because of interfering overhanging parts of the loom. It is desirable, therefore, to provide supporting means for permitting the receptacle to be swung out of normal bobbin receiving position to permit of convenient removal of bobbins from the receptacle. In present commercial constructions, it is usually necessary manually to return the receptacles to bobbin receiving position and as a result, the passageway between the looms is often unnecessarily obstructed.

One object of the present invention, therefore, is to provide improved means for supporting a bobbin or filling carrier receptacle in filling carrier or bobbin receiving position and for permitting the bobbin receptacle to be moved into position to permit bobbins to be removed therefrom and then to return automatically to bobbin receiving position. To this end, and in accordance with one feature of the invention, a pair of supporting members are provided, one being fixed to the loomside and the other being fixed to or formed as a part of the filling carrier receptacle, said supporting members being arranged to interengage and support the receptacle in filling carrier receiving position and arranged for angular movement relatively to each other to permit the receptacle to be moved out of filling carrier receiving position. The illustrated receptacle is formed of heavy cloth such, for example, as duck or canvas but it is evident that a rigid receptacle formed of wood or metal could be used if so desired.

With the above and other objects and features in view, the invention will now be described with particular reference to the accompanying draw-

2

ings which illustrate a preferred embodiment of the invention and in which:

Fig. 1 is a detail view in front elevation of a position of a loom in which the present invention is embodied;

Fig. 2 is a view in side elevation of a receptacle secured to a loom;

Fig. 3 is a view, on an enlarged scale, of one of the supporting members;

Fig. 4 is a plan view showing the supporting members in receiving position on a loom side;

Figs. 5 and 6 are perspective views of the supporting members;

Fig. 7 is an assembled view of said supporting members in supporting position; and

Fig. 8 is a bottom plan view of one of the supporting members which is secured to the receptacle.

The invention is shown in the drawings as being applied to an automatic loom of the filling replenishing type and which is of usual and well known construction. Consequently, only so much of the right hand side of the loom is shown and described as is necessary to a complete understanding of the present invention.

As shown in Figs. 1 and 2, the filling or bobbin receptacle 10 is mounted on the right hand side of the loom. Only a portion of the right hand side frame 12, the reciprocating lay 14 and the rotatable battery 16 are shown. The other parts of the loom are of usual construction and, accordingly, are not described herein.

The reciprocating lay is provided with a shuttle box 18 into and out of which the shuttle (not shown) is picked by a picker stick. When the filling on the filling carrier in the shuttle is substantially exhausted, the parts of the mechanism are conditioned to transfer a new filling carrier from the rotatable battery 16 and into the shuttle to replace the exhausted or substantially exhausted filling carrier which is ejected through the hollow of the shuttle and into the bobbin receptacle 10.

The receptacle 10, shown in the drawings, is preferably formed of flexible textile material, such as duck, but it may be made of other suitable material if so desired. The receptacle 10 is generally substantially trapezoidal in cross section but it may be of any other suitable shape if so desired. The illustrated receptacle 10 is of substantially the same shape as the receptacle shown and described in an application for United States Letters Patent Serial #483,094 filed April 15, 1943, now Patent No. 2,350,317 in the names of Edward C. Nichols and Willard C. French.

The receptacle 10 is provided with a hem 18 at its upper end position for receiving a rod 20 which is bent into a suitable generally trapezoidal shape as shown best in Fig. 4. The hem 18 is interrupted as best shown in Fig. 3 to permit the ends 22, 24 of the frame or rod 20 to be clamped in a supporting member 26. This supporting member 26 is preferably formed of cast iron and is provided with a body portion having a substantially vertically extending boss 28 having a hole 10 for receiving the end 22 of the rod or frame 20. The member 26 is also provided with a rearwardly and upwardly extending boss 30 having an opening for receiving the end 24 of the rod 20. The end 22 is maintained in position in the supporting block 26 by a cap screw 32 which is threaded into the boss 28. The end 24 is similarly maintained in position by a cap screw 34. The supporting member 26 is provided with a downwardly extending flange 36 which forms, with the main vertical wall of the member 26, a groove 38 which is substantially wider at its rearward end than at its forward end. The base of the groove 38 extends forwardly and downwardly.

A cooperating supporting member 40 is fixed to the loom side 12 by a bolt 42. The member 40 is provided with an inclined lip 44 which projects downwardly and forwardly. The lip 44 is parallel to the main body 46 of the member 40 but is spaced a substantial distance therefrom to permit relative angular movement between the members 26 and 40 when it is desired to swing the receptacle 10 to permit removal of bobbins therefrom without interference from the rotary hopper 16 and the transfer mechanism 48 associated therewith. The member 40 is provided with a stop 50, which limits rearward movement of the member 26. The lower edge of the stop 50 is engaged by an extension 52 formed as a part of the support 26. The support, as best shown in Fig. 4, is located so far rearwardly that the receptacle 10 tends to rotate the support 26 in a counter clockwise direction as viewed in Fig. 7. The stop 50 effectively prevents such rotation and hence the receptacle 10 is supported in bobbin receiving position.

The parts of the present device have been described in detail but it may be well for a better understanding of the invention to summarize briefly the assembly and advantages thereof. When it is desired to place the receptacle 10 in bobbin receiving position, the receptacle is grasped at the forward end 54 of the frame 20 and the lip 44 of the member 40 is received in the groove 38 of the member 26. The parts are then slid relatively to each other until the end 56 of the member 26 engages the stop 50 on the member 40. The receptacle and frame will tend to rotate about the rear edge of the extension 52 of the supporting member 26 so that the lip 44 and the downwardly extending flange 36 are in contact substantially throughout their length. When it is desired to swing the receptacle 10 out of position to permit bobbins to be removed therefrom the receptacle is swung in a clockwise direction, as viewed in Fig. 4, to move at least a portion of the receptacle from beneath the hopper and transferring mechanism, the member 26 will swing to the left a distance controlled by the width of the groove 38. The receptacle 10, however, must be held manually in displaced position and when released it will automatically return to bobbin receiving position.

Having thus described my invention what I

claim as new and desire to secure by Letters Patent of the United States is:

1. In a loom, a bobbin receptacle comprising a bag formed of flexible material, a rigid frame surrounding the mouth of the bag, a support member fixed to said frame and having a laterally extending depending portion forming a groove, a shoulder on said support member, a cooperating support member fixed to the loom and having an upstanding rib received in said groove in the other support member and an abutment arranged to engage the shoulder on the other support member.

2. In a loom, a bobbin receptacle comprising a bag formed of flexible material, a rigid frame surrounding the mouth of the bag, a support member fixed to the side of said frame and having a laterally extending depending portion forming a groove which is substantially wider at its forward portion than at its rearward portion and a shoulder on said support member, and a cooperating support member fixed to the loom frame and having an upstanding rib fitting into said groove and an abutment against which the shoulder on the support member fixed to the frame bears to maintain said bag in position.

3. In a loom, a bobbin receptacle comprising a bag formed of flexible material, a rigid frame surrounding the mouth of the bag, a support member fixed to the side of said frame and having a laterally extending depending portion forming a groove which is substantially wider at its forward portion than at its rearward portion and a shoulder on said support member and a cooperating support member fixed to the frame of the loom and having an upstanding rib of substantially uniform width fitting into said groove and an abutment against which said shoulder bears to maintain said bag in position, said cooperating support members being movable angularly relatively to each to permit the bag to be swung manually into and out of normal position.

4. In a loom, filling replenishing mechanism, 45 a bobbin receptacle comprising a bag formed of flexible material, a rigid frame secured to said bag and surrounding the mouth of said bag, a support member fixed to said frame and having a laterally extending depending portion forming a wall of a groove wider at its forward portion than at its rearward position and a shoulder, and a cooperating support member fixed to the frame of the loom and having an upstanding rib of substantially uniform width fitting into said groove and an abutment seated against said shoulder to maintain said bag in position below said filling replenishing mechanism.

5. In a loom, filling replenishing mechanism, a bobbin receptacle comprising a bag formed of flexible material, a rigid frame secured in a hem surrounding the mouth of said bag, a support member rigidly secured to said frame and having a main body portion and a laterally extending depending flange forming a groove wider at its forward end than at its rearward end, a shoulder formed on said main body portion, and a cooperating support member fixed to the frame of the loom below said filling replenishing mechanism, said last-named support member having an upstanding rib of substantially uniform width received in said groove to limit angular movement of said bag and an abutment against which said shoulder is seated to maintain said bag in position below said filling replenishing mechanism.

6. In a loom, a loom frame, filling carrier re-

plenishing and expelling mechanism, a filling carrier receptacle comprising a bag formed of flexible material and having a hem surrounding its mouth, a rod bent substantially in the form of a trapezoid and threaded through said hem to hold the mouth of the bag open, a support member having openings for receiving the ends of said rod and forming a rigid support for said bag, a depending laterally extending flange on said support member defining with the body portion of said support member a forwardly flaring groove, a shoulder formed as a rearward extension of said main body portion, a cooperating support member fixed to said loom frame below said filling carrier replenishing and expelling mechanism, an upstanding rib on said cooperating support member received in said groove and limiting lateral swinging movement of said receptacle, and an abutment on said cooperating support member having a lower surface against which said shoulder is seated to maintain said receptacle in normal position below said filling carrier replenishing mechanism.

7. A support for a receptacle for receiving expelled filling carriers comprising a rod bent substantially into the form of a trapezoid, a support member comprising a main body portion having openings in which the ends of the rod are received, means for securing the ends of said rod in said openings, a laterally extending depending flange forming a forwardly flaring groove with one wall of said main body portion,

a shoulder on said main body portion, a cooperating support member adapted to be fixed to a loom frame, an upstanding rib of substantially uniform width on said cooperating support member and arranged to be received in said groove, and an abutment of said cooperating support member having a lower surface against which said shoulder is arranged to be seated to maintain said receptacle in position.

- 10 8. A support for a receptacle for receiving expelled filling carriers comprising a rod bent substantially into the form of a trapezoid, a support member comprising a main body portion having openings in which the ends of the rod are received, means for securing the ends of said rod in said openings, a laterally extending depending flange forming a forwardly flaring groove with one wall of said main body portion, the base of said groove being substantially flat and inclined downwardly and rearwardly, a shoulder formed on said main body portion below and rearwardly of said groove, a cooperating support member adapted to be fixed to a loom frame, an upstanding rib of substantially uniform width formed on said cooperating support member and arranged to be received in said groove, said rib being inclined downwardly and rearwardly, and an abutment located below and rearwardly of said rib and having a lower surface against which said shoulder is seated to maintain said receptacle in position.

GEORGE F. BELFORTI.
